UNITED STATES PATENT OFFICE

JOHN Q. SHERMAN AND ALBERT W. METZNER, OF DAYTON, OHIO, ASSIGNEES, BY
DIRECT AND MESNE ASSIGNMENTS, TO THE STANDARD REGISTER COMPANY

MANIFOLDING REGISTER

Application filed April 18, 1925. Serial No. 24,193.

Our invention relates to manifolding machines, and more particularly to manifolding registers, which are operated by a small motor.

5 In providing for electrical operation of manifolding registers, of the type in which the paper feed is calculated to issue predetermined form lengths of paper, at each cycle of operations, there are a number of features to be arranged for. The paper feed must have a definite cycle with a latch of some character which releases it for single complete revolutions, and then latches it again. The motor must have a switch, and there must be 10 mechanism such that when the paper feed is positively stopped, the motor must be permitted to revolve a little further and the driving electric circuit must be broken.

In our United States Patent No. 1,437,949, 20 dated December 5th, 1922, we have shown a mechanism which provides for the features outlined in connection with a particular type of motor which shuts itself off when subjected to excessive load, and in which the drive to 25 the paper feed includes a friction which applies the excess load to the motor, when the paper feed is stopped.

The present invention relates to improvements in the mechanism shown in the patent 30 referred to.

Our object in the present construction is to provide for a motor driven operating device for manifolding machines which is a unit of itself, which can be mounted on a machine in 35 place of the regular operating handle, and the machine converted into an electrical type without other change.

Our object is to simplify the friction device of the former construction and embody all 40 of the driving features in a very compact frame, carrying stops, reduction train, switches and the like, thereby providing a complete driving unit.

Our object is to provide in addition to the 45 structure of the motor we formerly used, an automatic switch cut-out which gives a starting impulse to the automatic shut off features of our former construction. This cut-off would enable us to do away with the automatic friction cut-off should this be desirable,

and provides against the failure of the friction cut-off, in case the driving friction to the feed shaft connection should become too loose to result in the automatic action.

Our object further is to provide for the paper feed release, now located on the motor drive unit, being so located as to result in the operator moving the paper feed release when he operates the switch. It is to our minds undesirable to have the switch and the paper feed release element all part of one lever train, and connected operatively to each other, as this requires braking devices and a complicated structure by means of which to avoid the placing of excessive load on the motor before it starts its operation, and prevents releasing the paper feed, or releasing the motor as a selective particular operation, should anything get out of shape in the operation of the machine.

These several objects we accomplish by that certain construction and arrangement of parts to be hereinafter more specifically pointed out and claimed.

In the drawings:

Figure 1 is a plan view of the preferred structure, showing a fragment of a manifolding machine frame.

Figure 2 is a side elevation of this device.

Figure 3 is a front elevation of the said 80 device.

Figure 4 is a detail of the latch and release mechanisms.

Figure 5 is a detail of the paper feed release bar and pawl.

Figure 6 is a detail of the motor switch plunger kick-off lever.

Figure 7 is a detail, the parts being separated, of the friction drive device forming part of the motor unit.

Figure 8 is a detail side elevation, taken from the inside of a modified form of paper release and switch operating member.

Figure 9 is a side elevation of a motor unit having said release of Figure 8 embodied therein, in place on a register.

Figure 10 is an end elevation of the parts shown in Figure 9.

Figure 11 is a detail of the feed release bar of the modified type.

Figure 12 is a like view to Figure 11 showing the pawl in place on the bar.

Figure 13 is a side elevation of the parts in Figure 12.

Figure 14 is a detail of the switch kick-off pawl.

Figure 15 is a detail section of the motor itself, showing the connections, of the first modification, on the switch shaft.

10 Referring briefly to the motor, we primarily refer to our Letters Patent heretofore referred to. The case of the motor is formed as a housing 1 for the rotor and field 2 and 3, and the commutator 4. The rotor shaft 5 extends upwardly through a portion 6 of the casing, which portion 6 is expanded at 7 to house the driving worm gear. The rotor shaft 5 is formed with threads, of a worm type, at 8. The switch is mounted on the top 15 of the portion 6 of the housing, in an added box 9. It is formed with contacts 10, which are connected together by the fins 11 on the plunger 12. The fins are given a positive make and break by a coiled spring set around 20 the plunger in a manner that is familiar in switch practice. The plunger is mounted in a spring depressed housing 13 that slides in the upper portion of the casing part 6, and this housing engages the upper end of the rotor 25 shaft.

When the rotor shaft is not permitted to revolve because of stoppage of the worm wheel that it engages and drives, the action will be to feed the rotor shaft and rotor upwardly, 30 the shaft acting as a screw, which in turn presses up on the housing of the switch plunger, and throws open the switch.

Referring to Figure 7 it will be noted that the worm wheel 14 is provided with a spindle 40 15, which engages in a bearing formed in the boss 7^a of the housing portion 7, of the motor frame. This worm wheel meshes with the worm, when in place, and carries on its face a conical disk 16.

45 The drive connection for the feed shaft of the manifolding machine is formed as a friction cone 17 mounted on a spindle 18, which passes through the spindle 15, and projects with a threaded end 19 at the outside 50 portion of the frame part 7. A spring 20 is set over the portion 19, and nuts 21, mounted on the threads thereof, thereby compress the spring and draw the friction cone into the friction disk, providing a friction drive for 55 the spindle 18.

On the outer portion of the cone is mounted a cam 22, having a nose 23, which serves together with a lever to be described, as a paper feed stop. This cam has also a stud 24 thereon 60 which cooperates with a pawl and slide bar, to give an upward impetus to the switch plunger of the motor, serving to throw off the motor as the feed comes to a stop.

The spindle 18 has in addition to the friction cone cam and stud, a fitting for engage-

ment with the end of the feed shaft of the manifolding machine. The shaft is indicated at 25, and has a slot in the end terminating in a rounded portion 26. There is also a pin 27 in the shaft, which acts as a key for the usual operating handle. It will be understood that this is merely one particular kind of a connection for the operating handle of a feed shaft in manifolding registers, the point being that the spindle of the friction cone has a device similar to the handle, which would naturally be modified to suit the type of machine upon which the motor unit was to be mounted. In this instance the friction cone spindle is fitted with 75 a collar 28, which is shaped to fit over the end of the feed shaft and is notched out to engage over the pin 27. A cotter pin or other form of pin is inserted through the holes 80 in the collar and through the rounded portion 26 of the slot in the end of the feed shaft.

Thus in the particular example shown, the connection of the friction spindle is a mere matter of replacement for the usual manual 90 feed handle on the feed shaft.

The motor itself has a strap 30 secured thereto, which is bolted as at 31 to the side of the manifolding machine, indicated at 32.

The stop levers and controls are mounted 95 on the motor casing, against the housing portion 7. In both instances the mounting device is in the form of a plate 33, screwed to the seat 34, that is formed within the open side of the frame portion 7.

This plate closes the said frame portion except for a central clearance for passage of the cam portion on the friction cone. In order to insure against oil leakage we may arrange within the housing portion 7, a conical shaped strip of thin metal 34^a, engaging the seat 34, and wiping the rear face of the concave plate, that is part of the worm wheel.

Referring to the common features of the two devices, (Fig. 8) there is a lever 35 mounted over a stud 36, said lever having an elongated slot arranged over said stud, and the stud being located on an extended portion from the plate 33.

A spring 37 tends to pull this lever upwardly. The lever has a hooked end 35^a which lies under influence of the spring against the cam 22. The nose on the cam engages the end of the lever at the end of each single revolution of the friction cone spindle, 110 and is thus brought to a positive stop.

The sliding bar 38 is provided, and held on a stud 39, which engages a slot in the bar. The bar is held up by a spring. On the bar is a pawl 40 which is engaged by a spring 41 to hold it normally against an ear 42 of the bar. The pawl can swing in the other direction from the ear against spring tension.

A projection 35^b on the top edge of the 120

lever 35 lies in the path of this pawl and when the lever is depressed, the pawl strikes the lever, thereby throwing its hook out of engagement with the cam, whereupon the tension of the mechanism will move the cam nose far enough beyond the hook 35^a to prevent further engagement. Should the bar 38 be held in depressed position, the pawl will not interfere with the lever 35 being caught up by

10 the cam nose on its next revolution because the pawl will swing against its spring, away from the projection on the lever, so as to permit the lever to move up under influence of the spring 37, far enough to engage the cam again.

15 In the preferred form of device, the bar 38 is provided at its upper end with a turned over portion 38^a which has a hole in it, sufficient to clear the button 43 on the top of 20 the switch plunger. The hole will be positioned just above the said button, with the button lying partially in the hole, in our preferred structure. It will also have a lip or tongue 44, which has a hole to freely clear, 25 but to be guided upon the switch plunger. The tongue 44 will be far enough down on the plunger to prevent the head from operating the lever in the operation of depression sufficient to throw the switch.

30 Also mounted on the plunger rod, and in this instance fast on the plunger, is another bar 45, which extends down into proximity with the cam on the friction cone spindle, and is there projected across the top of the 35 cam at 45^a. The stud on the cam is set to strike up the bar end 45^a, and thus to give the switch plunger an upward thrust sufficient in most instances to throw the switch entirely out. If the operator leaves his hand 40 on the switch button and the top of the bar 38, this kick-off device will warn him to let go.

45 In the second form the kick-off device is in the form of a pawl 50 which is positioned to be struck up by the stud 24 on the cam, but in this instance engages a stud 50^a extending inwardly from the bar 38. The bar 38 is provided with the tongue 51 which in this instance engages over the switch plunger 50 as does the tongue 44, but is fast on the rod, or so near the top as to be operated by the button of the plunger when depressed. The depression of the switch plunger will operate the sliding bar to release the paper feed before the switch is thrown to close the circuit to the motor, and the stud on the cam throws up the bar 38 so as to push the plunger head upwardly and release the switch at the moment that the paper feed is positively 60 stopped.

It will be evident without description of the mode of operation of the register, that a single manual operation will pick up both the paper feed latch, and start the motor.

65 The entire driving mechanism is in the mo-

tor and is removable or mountable as such in place of a manual operating handle. The various features of advantage in this type of feed for manifolding machines are covered in our patent heretofore referred to, to which reference is made.

70 Referring to the usual manifolding register, in which a feed shaft 25 (Fig. 7) engages the paper to be fed, the operator will depress the motor switch plunger and the accompanying bars, which will result firstly in a release of the latch mechanism and then secondly in an energizing of the motor, through closure of the switch. The motor drive will then rotate the feed shaft one complete revolution, thus feeding a measured quantity of paper. As the close of the revolution approaches, the kick-off device will throw up the motor switch plunger which stays down due to the snap switch structure 75 described, until forced upwardly by automatic action of the motor, which action is thus accelerated by the kick-off. Immediately following the kick-off, the cam nose will come against the latch and the paper feed 80 shaft will be stopped, completing a feed cycle.

85 Having thus described our invention, what we claim as new and desire to secure by Letters Patent, is:—

90 1. In combination with a manifolding machine having a feed shaft for operating a paper feed, an electric mechanism comprising in one structure switch controlled circuit connections, a driven member for said shaft, and a positive stop, means for opening the 100 switch automatically upon positive stopping, means for releasing said stop, and means on the driven member for accelerating the action of the automatic switch opening means.

95 2. An electric driving element for manifolding machines having a casing, a motor and switch on the casing, a driven element in the casing adapted for connection with the manifolding machine, a stop for the driven element, having a projection for release of the same, and adapted to automatically engage after desired cycles of movement of the driven element, said projection independent of the switch, but located in the same path therewith so as to permit a single manual movement to release the stop and close the 110 switch.

115 3. An electric driving element for manifolding machines having a casing, a motor and switch on the casing, a driven element on the casing adapted for connection with the manifolding machine, a stop for the driven element, having a projection for release of the same, and adapted to automatically engage after desired cycles of movement of the driven element, said projection independent of the switch, but located in the same path therewith so as to permit a single manual movement to release the stop and close the switch, and means under control of the driven element 120 125 130

for throwing the switch open in timed relation to the automatic operation of the stop.

4. An electric driving element for manifolding machines having feed mechanism, comprising a motor and switch therefor, a member driven by the motor, a spindle passing through said member, spring means enforcing stress on said spindle, a friction member engaging the driven member and mounted on said spindle, and connections for said spindle with the feed mechanism of the manifolding machine, a stop member on said spindle, a latch for said stop and operating means for said latch adapted to trip said latch and then release it automatically.

5. An electric driving element for manifolding machines having a casing, a motor and switch on the casing, a driven element on the casing adapted for connection with the manifolding machine, a stop for the driven element, a latch for the stop, and adapted to automatically engage after desired cycles of movement of the driven element, said latch provided with an operating bar having an aperture therein, and said switch having an operating element in the form of a rod located in line with said aperture for the purpose described.

6. A motor control structure in electrically driven manifolding machines comprising a motor driven member connected to the manifolding machine mechanism, a cam thereon having a nose, a spring lever positioned to engage said cam, and retain said nose in a positive stopping action, a manually controlled element for closing circuit through the motor, and a sliding element for operating said lever, said closing element and sliding element lying in the same path so that a single manual depression of both can be accomplished in the same movement.

7. A motor control structure in electrically driven manifolding machines comprising a motor driven member connected to the manifolding machine mechanism, a cam thereon having a nose, a spring lever positioned to engage said cam, and retain said nose in a positive stopping action, a manually controlled element for closing circuit through the motor, and a sliding element for operating said lever, said closing element and sliding element lying in the same path so that a single manual depression of both can be accomplished in the same movement, a trip on the motor structure for moving said manually controlled circuit closing element, and a projection on the motor driven member to engage said trip in timed relation with the location of the said cam nose.

60 JOHN Q. SHERMAN.
